UNITED STATES PATENT OFFICE.

SAMUEL E. PURDUM, OF MACOMB, ILLINOIS.

VENDING MACHINE.

Application filed May 25, 1925. Serial No. 32,800.

To all whom it may concern:

Be it known that I, SAMUEL E. PURDUM, a citizen of the United States, residing at Macomb, in the county of McDonough and 5 State of Illinois, have invented a new and useful Vending Machine, of which the following is a specification.

This invention relates to a check-control device especially designed for use in connection with vending machines, the primary 10 object of the invention being to provide a device of this character of a novel construction to insure against a coin other than the coin designated to operate the machine, operating the locking mechanism.

Another object of the invention is to provide a device of this character which when operated, will act to throw the coin into a coin receptacle supported thereunder.

20 A further object of the invention is to provide a sliding actuating member having its inner extremity bent upwardly and forwardly to constitute an ejector for throwing the article vended, from the machine.

With the foregoing and other objects in view which will appear as the description proceeds, the invention resides in the combination and arrangement of parts and in 30 the details of construction hereinafter described and claimed, it being understood that changes in the precise embodiment of the invention herein disclosed, may be made within the scope of what is claimed, without departing from the spirit of the invention.

Referring to the drawing:

Figure 1 is a front elevational view of a vending machine equipped with a coin-control device constructed in accordance with 40 the invention.

Figure 2 is a horizontal sectional view through the upper portion of the check-control device.

Figure 3 is a vertical sectional view 45 through the device, illustrating the position of the ejector when it has been moved to eject an article.

Figure 4 is a vertical sectional view 50 through the device illustrating the position taken by the locking arm when a counterfeit coin has been inserted in the machine.

Figure 5 is a sectional view through the device illustrating the position of the locking arm when engaged by a coin of the 55 proper size.

Figure 6 is a sectional view taken on line 6—6 of Figure 2.

Figure 7 is a sectional view taken on line 7—7 of Figure 2.

Figure 8 is a sectional view taken on line 8—8 of Figure 2.

Referring to the drawings in detail, the reference character 5 indicates the cabinet of a vending machine equipped with a check controlled device constructed in accordance with the invention, the cabinet in the present illustration comprising a plurality of vertical compartments in which articles are positioned.

The check-control device forming the essence of the present invention embodies a base plate 6 which is formed with an elongated cut out portion 7 formed with a circular end portion 8 that has a notch 9 formed in the wall thereof.

In the formation of the elongated cut out portion 7 ears are formed at a point substantially intermediate the ends thereof, the ears being indicated at 10 and provide bearings for the pin 11 that supports the locking arm 12 to be hereinafter more fully described. Slidably mounted on the plate 6 is a combined check receiving plate and ejector indicated at 13 which has one of its ends extended upwardly at 14 presenting a finger piece to be gripped by the operator to move the plate 13 in actuating the check-control device.

As shown by Figure 3 of the drawings, the opposite end of the sliding plate 13 is bent upwardly and forwardly, the extreme end thereof being bent downwardly at 15 providing an ejecting flange to engage the articles held in the compartments of the machine to force them from the machine.

Formed in the check receiving plate 13 is an elongated cut out portion 16 provided with a central coin receiving opening 17, the elongated cut out portion 16 being provided to allow the locking arm 12 to move upwardly through the coin receiving plate 13 when it has been actuated by a check or coin of the proper size.

Adjacent to one end of the elongated cut out portion 16 is a relatively small cut out portion 18 defining a locking shoulder 19 to be engaged by the shoulder 20 formed at the inner extremity of the locking arm 12, and it will be seen that the length of the locking arm 12 is such that if a coin such as

indicated at 24' as shown by Figure 4, is positioned in the coin receiving opening 17, and the coin is not of the proper size to engage the locking arm 12 at the proper time, the shoulder 20 will engage the shoulder 19, locking the plate 13 against rearward movement, or to a position where it may be brought forwardly to eject an article from the machine.

10 At the forward end of the locking arm 12 is a shoulder 21 which is adapted to engage the shoulder 22 of the plate 13 when the plate 13 is moved forwardly, thereby restricting forward movement of the plate 13 after it has been moved to eject an article from the machine.

15 The forward under edge of the arm 12 is inclined as at 23 so that when a coin such as indicated at 24 and illustrated by Figure 20 5 of the drawings, is positioned within the openings 17 of the plate 13, the coin may ride over this inclined surface, swinging the forward end upwardly and moving the shoulder 20 from a locked position as shown by Figure 4 of the drawing to an unlocked position as shown by Figure 5, allowing the plate 13 to move within the casing to a position where it may be brought forward to eject an article from the machine.

25 Mounted on the pin 11 is a spring 25 which has a portion thereof coiled around the pin, the ends thereof engaging the under side of the plate 6, the intermediate portion of the spring engaging the locking arm 12 to normally urge the inner end of the locking arm 12 upwardly. Thus it will be seen that when a coin has been inserted and has moved to actuate the arm 12, the spring 25 is placed under tension to the end that 30 when the coin has moved to a position within the openings 17, directly over the opening 8, the coin will be forced through the plates 13 and 6 and dropped into a coin receptacle positioned thereunder.

40 45 In the formation of the device, the plate 6 has portions thereof stamped therefrom, the portions being indicated at 26 and bent

upwardly to provide guides for the plate 13. Cut out portions 27 are also provided adjacent to the edges of the plates 6 and 50 55 accommodate the tongues 28 of the table 29 supported thereabove to secure the table 29 to the plate.

The table 29 includes inwardly extended flanges 30 that overlie the plate 13 and prevent the plate from moving upwardly when the coin carried thereby engages the under edge 23 of the arm 12. This table receives articles that drop from the article compartments of the machine so that they may be 30 engaged by the member 15 and thrown from the machine.

As before stated when a coin of the proper size is positioned in the machine, the coin will engage under the forward end of the locking arm 12 moving it to a position as shown by Figure 5 of the drawing, but if a coin of too small a diameter is positioned in the opening 17, the shoulder 20 will remain behind the shoulder 19 owing to the fact that the shoulders will be in cooperative relation with each other prior to the engagement of the coin with the forward end of the arm 12.

In view of the foregoing detail description, it is believed that a further detail description as to the operation of the device is unnecessary.

I claim:—

In a check-control device, a base plate, 80 an ejector plate slidably mounted on the base plate and having a coin receiving opening, a locking arm pivotally supported under the base plate, the ends of said arm adapted to engage the ejector plate to restrict movement thereof, and said locking arm adapted to be moved to its inactive position by a coin carried by the ejector plate.

In testimony that I claim the foregoing 90 as my own, I have hereto affixed my signature.

SAMUEL E. PURDUM.
